Primary Examiner — Cynthia R Underwood

CLAIM

I claim the ornamental design for a tablet case, as shown and described.

DESCRIPTION

FIG. 1 is a front elevational view of a tablet case showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a perspective view thereof in use, showing the front view of the standing statues;
FIG. 8 is another perspective view thereof in use, showing the rear view of the standing statues; and,
FIG. 9 is a perspective view thereof, illustrated in an unfolded position.
The broken lines shown depict environment that forms no part of the claimed design.

1 Claim, 9 Drawing Sheets
